COAXIAL PROPELLER DRIVE AND
MOUNTING

Henry S. Swaskey, Monessen, Pa.

Application November 8, 1939, Serial No. 303,465

2 Claims. (Cl. 170—135.5)

My invention relates to structural arrangements whereby aeroplane propellers or the like are mounted co-axially with respect to the propeller shaft and in driven relation thereto, and the primary object of the invention is to provide simplified and more efficient arrangements of this character for a single propeller or for two or more co-axial propellers, turning in different directions.

Other important objects and advantages of my invention will be apparent from a reading of the following description taken in connection with the drawings, wherein for purposes of illustration I have shown preferred embodiments of my invention.

In the drawings:

Figure 1 is a general vertical longitudinal sectional view taken through an arrangement in accordance with the present invention whereby at least two propellers are co-axially mounted and driven in opposite directions.

Figure 2 is a transverse vertical sectional view taken through Figure 1 approximately on the line 2—2 and looking toward the left in the direction of the arrow.

Figure 3 is a fragmentary elevational view on a reduced scale looking from right to left in Figure 1.

Figure 4 is a similarly reduced elevational view of the forward side of the bearing retainer.

Figure 5 is a view similar to Figure 1 showing an arrangement in accordance with the invention involving a single propeller.

Referring in detail to the drawings, and first to the dual propeller arrangement illustrated in Figures 1 and 2 of the drawings, the numeral 5 generally designates a substantially stationary portion of the engine (not shown), in the present case an aeroplane engine, which supports a horizontal tubular cylindrical part 6, with the propeller shaft 7 extending therethrough beyond the bearing 8 in the motor housing, the said shaft 7 extending in spaced relation to the interior walls of the part 6 and having its front end extending through a bearing bushing 9 adjacent the right hand end of the part 6. The right hand end of the propeller shaft is splined as indicated by the numeral 10. The numerals 11 and 12 designate co-axial propellers which have their blades pitched in opposite directions for substantially similar aero-dynamic action when rotating in opposite directions. Each of these propellers has a hub 13 which surrounds the part 6 and is rotatably supported thereon by a pair of oppositely pitched roller bearings 14. A separator 15 in

the form of a cylinder fitting the outside of the part 6 is keyed to the part 6 as indicated by the numeral 16 and further locked in place by a set screw 17 opposed to the key 16, and this separator has its left hand end bearing against the right hand bearing 14 of the propeller 11 and has its right hand end bearing against the left hand bearing 14 of the propeller 12. On the facing sides of both propellers are respective ring gears 18, 19, which are equipped with beveled teeth 20, the ring gears being held in place by studs 21 entering the hubs of the propellers. A beveled idler pinion 22 has a roller bearing 23 revolvably mounting it on a stub shaft 24 which projects from a boss 25 extending radially from the separator 15 between the propellers, and this pinion 22 is held in mesh with both of the ring gears 18 and 19 by a retainer 26 secured to the outer end of the stub shaft 24. By means of these arrangements the propellers 11 and 12 are free to turn relative to each other and relative to the motor housing extension 6, but only in opposite directions. The propeller 12 is held in place by engagement of the retainer plate 27 with the right hand one of its roller bearings 14, this plate 27 being circular as indicated in Figure 4 and of a diameter to extend its edges beyond the sides of the part 6 to engage the mentioned bearing, this plate being provided with a number of stud holes 28 which receive studs 29 which enter the right hand end of the part 6. A concavo-convex heavy plate 30 of circular form has an axial opening 31 therein with splines thereon to fit the spline grooves 10 on the right hand end of the propeller shaft 7 so that the plate 30 is secured to the shaft for rotation therewith and support thereby. A suitable number of circumferentially spaced indentations 32 are provided in the outer side of the plate 30 and these have communication with stud holes 33 which accommodate studs 34 in the position indicated in Figure 1, with the studs 34 threaded into the hub of the right hand propeller 12, thereby rigidly connecting the member 30 with the propeller 12 so as to impart to the propeller 12 the rotary motion of the propeller shaft 7 as it is turned by the driving engine. It is to be observed that the concavity 35 of the plate 30 is sufficient to provide the desired clearance for adjustments of the propellers along the member 6 for taking up wear and for other purposes. As shown in Figure 2, the boss 25 has an opening 36 in which the beveled pinion 22 is mounted, the upper part of the boss defined by the opening being the retainer 26 referred to, and the stub shaft 24 extending across this open-

ing and in the lower part of the stud and in the retainer portion 26. It is to be observed that the set screw 17 not only assists the key 16 in preventing relative rotation of the member 15 on the member 6, but also locks the member 15 against longitudinal movement relative to the part 6.

Referring now to the embodiment of the invention shown in Figure 5, which illustrates a single propeller arrangement in accordance with the present invention, the numeral 5a designates the aeroplane or other engine housing, the numeral 6a the tubular extension thereof on which the propeller 12a is revolvably supported by the pair of oppositely angulated bearings 14a the right hand one of which is engaged by the retainer plate 27a secured to the right hand end of the member 6a by the studs 29a. In this case the left hand bearing 14 may engage a stop shoulder 37 adjacent the housing 5a instead of the housing itself as in the first described embodiment, in opposition to the retainer plate 27a. The propeller shaft 7a extends through the part 6a and through a bearing bushing 9a and also through the plate 27a where it has the splined portion 10a which is splined in the opening in the plate 30a which has countersunk studs 34a threaded into the hub 13a of the propeller to operatively connect the propeller shaft with the propeller. Also similar to the arrangement of the first described embodiment is the bearing arrangement 8a in the propeller shaft housing for the propeller shaft which in this case is shown as a portion of the crankshaft 38, having one of the connecting rods 39 of the engine connected thereto and shown working in the cylinder 40.

Although I have shown and described herein preferred embodiments of my invention, it is to be understood that I do not desire to limit the application of the invention thereto, except as may be required by the scope of the subjoined claims.

Having described the invention what is claimed as new is:

1. In combination with an engine having a

stationary housing and a propeller shaft extending therefrom, a cylindrical tubular extension on said housing receiving said propeller shaft with the end of the propeller shaft extending axially therebeyond, a propeller having an annular hub rotatably mounted on said tubular extension, and an operative connection between said end of the propeller shaft and said propeller, another propeller having an annular hub rotatably receiving said tubular extension, said other propeller being positioned between the engine housing and the first propeller, and gear means operatively connecting the propellers for simultaneous rotation in opposite directions, said gear means comprising a sleeve on said tubular extension, said sleeve being located between the propellers, a radial boss on said sleeve including a radial stubshaft mounting a pinion, and ring gears on the facing sides of the hubs of the propeller meshed with said pinion.

2. In combination, an engine having a stationary housing and a propeller shaft extending therefrom together with a tubular extension on said housing surrounding said propeller shaft, first and second propellers having their hubs mounted on and spaced along said tubular extension, bearing means rotatably mounting said propellers on said tubular extension, a cap outwardly of the tubular extension and secured to one of said propellers, said cap being splined on the outer end of the shaft, the facing sides of said propellers being formed with ring gears, a pinion in mesh with both of said ring gears, and carrier means mounting said pinion on said tubular extension, said bearing means comprising an inner stationary tapered bearing and an outer axially adjustable bearing for each of said propellers, said carrier means being adjustable along said tubular extension, and an axially adjustable retaining washer secured to the outer end of said tubular extension and engaging the outer adjustable bearing of the adjacent propeller to hold the bearing means of both propellers in a predetermined position.

45.

HENRY S. SWASKEY.
